UNITED STATES PATENT OFFICE.

PAUL BAUMGARTEN, OF RICHMOND HILL, NEW YORK.

COMBINATION CHAIR AND WINDOW SEAT.

Application filed July 8, 1927. Serial No. 204,332.

This invention relates to chairs and in particular to one adapted for use as a window seat.

A particular object of the invention is to provide a chair which can not only be folded up when not in use but can be used as an auxiliary chair when desired, and can also be used for cleaning windows.

One of the difficult features in connection with the cleaning of windows by housewives, has been the necessity for the housewife sitting upon the window sill and then pulling the windows down so that they can be cleaned. It is an object, therefore, to provide a chair which may be placed out of the window and can be adjusted so that it forms a convenient seat for one desiring to clean the window and eliminates the necessity of sitting upon the narrow window ledge while the cleaning is going on.

A still further object of my invention is to provide a chair which, when in use as a window seat will afford a support for the back of the person sitting therein, so that the danger of falling backward will be reduced to a minimum and also the use of the hands in holding on to the window sill or sash will be dispensed with, thereby leaving both hands free to carry on the cleaning operation which can be done more quickly due to the more secure and comfortable seating of the cleaner and also rendering the cleaning operation safer.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in perspective of my improved combination chair and window seat, the auxiliary seat portion thereof being shown in its closed position.

Figure 2 is a fragmentary view in sectional elevation, the same being enlarged and arranged to show how the auxiliary seat will grip the edge of a window sill when the chair is being used as a window seat, and

Figure 3 is a cross-sectional view taken on the line 3-3 of Figure 2, showing the construction of the combination chair and window seat.

Referring to the drawings in detail, the

chair is indicated generally by the numeral 5 and comprises the main seat portion 6 which is grooved to receive the channel member 7, the channel member constituting at its front end, a holding hook 8 by reason of the fact that the metal at that point is crimped and bent to hook shape so that it will fit over the window sill 9. This channel member 7 constitutes an auxiliary seat and as illustrated in Figure 3, is provided in depending side portions 10 with the serrations 11, the serrations being shaped in the nature of teeth which are adapted to be engaged by a holding member so that the distance the auxiliary seat 7 can be drawn out is limited by the holding member. The main seat piece 6 is provided at its edges with the suitable binder or edge pieces 12 which are pivoted at their rear ends as at 13 to the brackets 14, these brackets being positioned on the leg members 15 of the stool or seat and having pivoted thereto, the legs 16 which are limited in their pivotal movement with regard to the legs 15 through the medium of the connecting chains 17 with which they are secured together at their lower ends.

It is evident that the chains will permit the legs to be spread apart a fixed distance and will also allow the legs to be folded together when the seat is to be stored away, for instance, in a closet or small space. The upper ends of the legs 15 are joined by the rods 18 and constitute a back support for the person occupying the seat, the lower ends of the legs 15 being connected by a connecting bar 19 as are also the lower ends of the legs 16. The upper ends of the legs 16 are pivoted as at 20 in a bracket 21 which is also carried on the side pieces 12 of the seat and act as a reinforcement at the point of connection of the legs to the body of the stool or seat.

In constructing my improved chair, it is quite evident that the main seat member 6 can be slotted transversely to receive the channel member 7, the slot being indicated by the numeral 22 in Figure 2, and when not in use, the channel member 7 or auxiliary seat, as it may better be termed, can be slid inwardly on the main seat 6 until the hooked end 8 thereof is substantially flush with the forward end of said main seat 6. When, however, it is desired to use the auxiliary seat in suspending the chair exteriorly of the window for the purpose of cleaning the sashes, the same may be drawn out and hooked over the edge of the window sill 9

and in order to provide for this extension of the auxiliary seat and to limit its movement relatively to the main seat, I have provided a bracket 23 which may be secured to one of the side pieces 12 and in position to form a journal or supporting member for the trip lever 24 which is pivoted therein as at 25 and is provided with a forwardly extending portion 26 adapted to operate pawls 27 for a purpose to be described.

The side pieces 12 of the main seat are also provided with brackets 28 in which are journalled the pawl rod 29 which at its center is provided with a spring holding sleeve 30 and it is encircled by a coil spring 31, the free end of which bears against the reinforced bottom 32 of the main seat member 6. Adjacent its ends, the pawl rod 29 carries the pawls 27, hereinbefore referred to 20 and one of these pawls is provided with an extended pin 33 which underlies the extended portion 26 of the trip lever 24, the noses of the pawls engaging in the serrations 11 formed on the depending portions 10 of the auxiliary seat 7 and being normally urged 25 into contact therewith through the medium of the coil spring 31 which surrounds the rod 29, as before described.

It is quite evident, therefore, that the 30 brackets 28 being connected to the main seat 6 through the medium of the side members 12 and the pawls carried by the shaft 29, operating to engage the auxiliary seat edge 7, that relative movement therebetween can 35 only take place in an outward direction when pressure is exerted on the trip lever 24 to release the pawls 27.

It is also evident that when the chair is 40 placed out of the window and the hooked end 8 of the auxiliary seat 7 is in place as shown in Figure 2 over the edge of the sill 9 that no relative outward movement of the main seat 6 can take place with the result that the person occupying the seat is perfectly safe and any danger of their falling 45 is eliminated due to the fact that the chair is provided with a substantial back and connections between the main seat 6 and the auxiliary seat 7 are strong enough to prevent any movement therebetween which 50 would endanger the person using the chair.

It is understood that a solid back may be 55 substituted for the rods 18 at the back of the chair. It is also evident that two trip levers 24 may be used and positioned at opposite sides of the chair, if desired, as these are features of construction which may increase the operativeness of the device from the standpoint of convenience, only.

It will be evident, therefore, that I have 60 provided a new and improved combination chair and window seat which may be effectively used as an auxiliary chair, in a kitchen, for instance, and which may be used conveniently for cleaning windows, so that 65 danger of falling is eliminated and the cleaning of windows from the outside may be greatly facilitated.

It is also evident that I have provided a 70 chair construction which is simple, which will operate efficiently, which will not get out of order and which may be folded up and placed out of the way in crowded quarters.

While I have illustrated and described my 75 invention with some degree of particularity, I realize that in practice various alterations therein may be made. I therefore reserve the right and privilege of changing the form 80 of the details of construction or otherwise 85 altering the arrangement of the correlated parts without departing from the spirit of the invention or the scope of the appended claims:

Having thus described my invention what 85 I claim as new and desire to secure by United States Letters Patent is:—

1. A combination chair and window seat comprising a main seat member, an auxiliary seat piece slidable therein and having 90 depending side edges, serrations in said edges, a hook on the forward edge of said auxiliary seat for attaching the same to a window sill, a pawl at each side of said seat for engaging in any one of said serrations 95 of the same side edge for limiting the movement of the auxiliary seat relatively to the main seat member and foldable legs on the main seat member.

2. A combination chair and window seat 100 comprising a main seat member, an auxiliary seat slidable therein, depending side portions on said auxiliary seat piece, a hook on the forward edge of said auxiliary seat for attaching the same to a window sill, a 105 transverse rod beneath said auxiliary seat and carried by said main seat, a pawl on each end of said rod for engaging in any one of the serrations of the same side edge 110 for limiting the movement of the auxiliary seat relatively to the main seat member and a trip lever for disengaging said pawls from said serrations.

In testimony whereof I affix my signature.

PAUL BAUMGARTEN. [L.S.]
